SOLENOID

Walter F. Kelley, Whitestone, N. Y., assignor to
Remington Rand Inc., Buffalo, N. Y., a corpora-
tion of Delaware

Application December 3, 1937, Serial No. 177,924

3 Claims. (Cl. 175—341)

This invention relates to solenoids and more particularly to improvements in solenoids which include a movable core or plunger as part of their mechanism.

5 Solenoids with movable cores designed to actuate other mechanisms by a change of current in their windings, possess many advantageous characteristics, such as high operating efficiency, small space required, and quick action. Consequently, they have been employed in many machines in a variety of designs.

The solenoid described hereinafter includes a casing which encloses all the moving parts, a fully protected winding and a plunger which has many unique features.

15 The principal object of this invention is to provide a solenoid with a plunger which will not bind in its casing.

Another object of the invention is to provide 20 a solenoid with a magnetic circuit of high efficiency.

A further object is to provide a protective covering for a solenoid to exclude dust and moisture from the internal moving parts.

25 Another object is to provide a casing from which the plunger of the solenoid may be removed easily and quickly for inspection.

A still further object is to provide a casing which is cheap to manufacture and easy to assemble.

30 Other objects and structural details of the invention will be apparent from the following description when read in connection with the accompanying drawing, wherein:

35 Fig. 1 is a central section view of the entire assembly;

Fig. 2 is a section taken along line 2—2 of Fig. 1;

Fig. 3 is a plan view of the insulating end disc which holds the electrical wiring in place;

40 Fig. 4 is a plan view of the slotted washer of insulating material which holds the terminal wires;

Fig. 5 is a plan view of a slotted phosphor bronze washer for supporting the winding;

45 Fig. 6 is a bottom view of the plunger showing the eddy current slots.

Although the solenoid is not necessarily in a vertical position when in use, it is always inclined enough to allow the plunger to be drawn back to its normal position by gravity. In this description the solenoid will be considered as standing in a vertical position (Fig. 1) and the upper portion will be called the top, while the lower portion will be called the bottom.

The fundamental principle underlying the operation of power solenoids is, that the production of motion is accomplished when and only when such motion reduces the reluctance of the entire magnetic circuit. The total reluctance of any magnetic circuit is equal to the combined reluctances of the separate parts, and if these parts are connected in series, then the total reluctance is equivalent to the algebraic sum of the parts. Since the magnetic flux must enter a free plunger 10 or armature at one point and leave it at another, there are always two air gaps in the magnetic circuit when the plunger is in its position corresponding to a value of current equal to zero. When the solenoid current is caused to flow, the 15 plunger or armature moves in a direction tending to shorten one or both air gaps and hence reduce the reluctance in the magnetic circuit. The present invention employs a design in which only one air gap is reduced, the other remaining constant. 20 Hereinafter, the two air gaps will be designated as "variable" and "constant," it being understood that the variable air gap produces the power necessary for motion and the constant air gap produces no power at all. 25

The outside casing of the solenoid consists of a soft iron tube 10, which is turned in at the bottom to form an annular shoulder 11, thereby forming a hole 12 in the bottom of the casing, large enough for the passage of an iron plunger 13 together with its bottom flange member 14, as will be explained later.

A second metal tube 15 also made from soft iron is inserted into the metal tube 10 as shown in Fig. 1 and retained in that position by the shoulder 11 and by virtue of a slit (not shown) in the tube 15, which permits it to act as an expansion ring. The metal tube 15 also acts as a support for a phosphor bronze washer 19 (Fig. 5) and an insulating disc 16 which forms part of the coil assembly. 35

Inside the metal tube 15 is placed another tube 18 of phenol resin as shown (Fig. 1). This tube provides a low friction surface for the bottom shoulder of the plunger to slide on and further helps to definitely determine the equivalent air gap in this portion of the magnetic circuit. 40

The solenoid winding 17 is wound upon a tube 20 made of phenol resin and is supported at each end by insulator discs 16 and 21. The winding is protected on the outside by the iron casing 10. The upper insulator disc 21 contains two notches 22 and 23 (Fig. 3), said notches being provided to permit the passage of the two ends of the solenoid winding, 24 and 25 (Fig. 2) 45

through the disc 21 to their respective connections. A guide ring 26, composed of insulation material (Fig. 4) containing a slot 27 is placed on the disc 21 so that the notch 23 of disc 21 is in line with the slot 27. This arrangement permits a wire to pass through the notch and slot as shown in Fig. 2.

The ends 24 and 25 (Fig. 2) of the solenoid winding 17 are soldered to wires 30 and 31, which wires in turn are wound around the ring 26 one-half of a turn and then passed through holes in a cap member 34. The insulation of the wires is slightly thicker than the ring 26 so that when the wires are placed in position, they protrude over the top of the ring. A shoulder 35 is formed in the top of casing 10 on which shoulder, cap 34 is positioned. The upper edge of cap 34 is chamfered to permit the edge of casing 10 to be turned over the chamfer and thereby permanently fasten the cap together with the solenoid winding 17, in place. When the casing 10 is crimped over the edge of the cap 34, said cap will be forced down until it engages shoulder 35. Since the insulation of the wires 30 and 31 is slightly thicker than the ring 26, the wires are consequently compressed by the cap 34 and tightly held in place. This prevents any movement of the wires at their soldered joints, thereby protecting them from breaking.

Secured to the cap 34 is a nipple 36 which is provided with a concentric hole 37, used as a guide for a non-magnetic rod 38 that may be fastened to the plunger of the solenoid or engaged by it. The nipple 36 is further provided with a bottom extension piece 40 which fits inside the insulator tube 20 and is partly supported therein. The nipple 36 is secured to the cap 34 by bolts or rivets or the two may be integrally cut from the same piece. A thread 41 is cut on the nipple 36 as indicated to aid in securing any mechanism which may be used to transmit the actuated plunger impulse.

The plunger 13 of the solenoid rides inside of the tube 20, said tube acting as a bearing for the plunger. In order to eliminate any binding action which might occur due to misalignment, a shoulder 42 is provided at the upper end of the plunger 13, the diameter of said shoulder being slightly smaller than the diameter of the insulator tube 20. The diameter of the remaining cylindrical portion is slightly less than the diameter of the shoulder so that the only point of contact between the cylinder 20 and plunger 13 is the shoulder 42.

At the bottom of the plunger 13, the flange member 14 is attached by any of the well known methods or the entire plunger and bottom flange may be turned from a solid piece of metal. The diameter of the flange is slightly less than the inside diameter of the phenol resin tube 18 in order to provide freedom of motion throughout the length of said tube without permitting any serious change in "air gap" length.

The space between the flange 14 and the inside iron tube 15 is termed "air gap" even though the space is filled almost entirely with phenol resin. Such parlance is common among those skilled in the art and is justified because the magnetic permeability of the phenol resin is the same as that of air. The "air-gap" in this face may vary depending upon other design factors and magnetic characteristics of the iron used. In any event the reluctance of this constant air gap may be made quite small in comparison to the variable air gap, because the area is so large.

The area extends around the periphery of the flange and is further enlarged by adding an extension 43 to the upper edge of the flange as shown.

A soft rubber washer 44 is placed on the cylindrical portion of the plunger 13, next to the flange 14 to act as a resilient shock absorber at the end of the plunger stroke. Another soft rubber washer 45 is placed inside the casing next to the shoulder 11 and forms a cushion for the plunger to fall upon when it returns under the force of gravity, after the magnet has been de-energized. This rubber washer 45 also forms a convenient means for holding the plunger within the casing when in use or for removing it for inspection. Removal is accomplished by distorting the washer so that it may be taken out through the hole 12 after which the plunger slides out without further obstruction.

When the coil is energized, a strong magnetic field is set up in the soft iron components and in the two air gaps. The path of these magnetic lines is as follows: From the plunger 13 where the greatest field strength is maintained, through the variable air gap 46, to the nipple extension 40, spreading out through the cap 34, down through the casing 10, into the tubing 15, across the constant air gap to the flange 14 and back to the plunger 13. Since a movement of the plunger 13 upward will shorten the variable air gap 46 and not change the constant air gap, the plunger will move up unless restrained by a force greater than that set up by the magnetic field. Assuming that the plunger is not so restrained, it moves swiftly upward gaining in tractive force as the variable air gap is shortened until the rubber washer 44 strikes the phosphor bronze ring 19 and stops the plunger motion. The top surface of the plunger never reaches the bottom surface of nipple extension 40 because the parts are so proportioned that the washer 44 stops the upward movement just short of contact.

Because freedom for motion must be provided between the flange and the tubular phenol guide, it follows that these parts may be eccentric by the necessary clearance and that the air gap at opposite ends of a diameter may vary by double the normal clearance distance. This tends to unbalance the magnetic field and the consequent radial or side-acting forces on the flange. The construction is also for the purpose of keeping the clearance at a minimum in order to maintain a minimum unbalance of the radial forces and friction.

The fact that the phenol tubing 18 constrains the flange 14 to a small lateral motion also keeps the main plunger 13 in line with the phenol tubing 20 which forms the inside of the electrical winding 17. The dimensions are such that the only contact the plunger 13 can make with the phenol tubing 20, is at the topmost portion 42, which by reason of its larger diameter, holds the remaining portion of the plunger clear.

The net result of this form of structure is a continuously aligned plunger with a constant low reluctance air gap at the flanged portion, and negligible friction due to lateral attraction.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of

my invention as hereinbefore set forth, and as hereinafter claimed.

What I claim as new, and desire to secure by Letters Patent, is:

- 5 1. In a solenoid having a tubular iron casing, a coil within said casing, an iron plunger axially movable partly within said coil and partly within said casing, iron flanges at each end of said plunger, the flange within said coil being only 10 slightly larger than the plunger, the flange within said casing being at least twice as large as the plunger, the periphery of each flange formed with a cylindrical surface concentric with the plunger, tubes of non-magnetic material mounted 15 within the said coil and within the said iron casing, whereby the periphery of the larger flange is movable within said tubing along the axis thereof but is laterally constrained to less than ten per cent of the distance between said flange 20 and said tubular iron casing.
2. In a solenoid having a tubular iron casing, a coil within said casing, a movable iron plunger within said coil of cylindrical form having flanged
- end portions, each having a diameter larger than the diameter of the middle portion thereof, two phenol resin tubular members, one positioned inside of said coil to slidably engage the smaller of said plunger flanges, the other positioned outside of said coil but inside of said casing to slidably engage the larger of said plunger flanges, the larger flange being at least twice the diameter of the smaller flange. 5
3. In a solenoid having an iron casing, a coil 10 and a movable iron cylindrical plunger, an iron flange formed on each end of said plunger, said flanges provided with coaxial cylindrical peripheries each having a diameter larger than the diameter of the middle portion of said plunger, 15 one of said flanges being slidably mounted within said coil, the second flange being slidably mounted within a non-magnetic tube adjoining the said casing, the second of said flanges being at least twice the diameter of the smaller flange and 20 both flange portions forming series elements in the magnetic circuit of said solenoid.

WALTER F. KELLEY.
